UNITED STATES PATENT OFFICE.

ANTON METZLER, OF ROCHESTER, NEW YORK.

ROTARY ENGINE.

1,152,034.

Specification of Letters Patent. Patented Aug. 31, 1915.

Application filed September 28, 1912. Serial No. 722,845.

To all whom it may concern:

Be it known that I, ANTON METZLER, a citizen of the United States, residing at Rochester, in the county of Monroe and 5 State of New York, have invented certain new and useful Improvements in Rotary Engines, of which the following is a specification.

The object of my invention is to provide 10 an improved form of rotary engine or motor. This and other objects of my invention will be fully illustrated in the drawings, described in the specification and pointed out in the claims at the end thereof.

15 In the accompanying drawings Figure 1 is a side elevation of my improved rotary engine with the reversing valve shown in section. Fig. 2 is a top plan view of my rotary engine partly broken away. Figs. 3 20 and 4 are sectional views of the reversing valve, the parts being shown in different positions from Fig. 1. Fig. 5 is a sectional view on the line 5^x—5^x in Fig. 2, with the reversing valve shown in a fourth position. Fig. 6 is a section on the line 6^x—6^x of Fig. 25 5. Fig. 7 is a perspective view of one of the piston blades. Fig. 8 is a detail view of one of the arms or links that support the piston blades. Fig. 9 is a perspective view 30 of the engine casing. Fig. 10 is a section on the line 10^x—10^x of Fig. 9. Fig. 11 is a perspective view of the piston shell with the blades omitted.

In the accompanying drawings reference 35 numeral 1 indicates the engine casing. This engine casing is provided with a cylinder 2 and a valve chamber 3. The cylinder is provided with admission and exhaust ports 4 and 5. The engine casing is also provided 40 with the ports 6 and 7 through which the steam passes from the steam space into contact with the piston blades, or vice versa. The engine cylinder is cylindrical where the pistons are adapted to rotate.

45 Mounted to rotate within the cylinder is the piston shell 8, which shell is cylindrical in form and has on the outer edges thereof the flanges 9 and 10, which flanges engage with and embrace the sides of the engine 50 cylinder 2, forming a steam or gas tight joint therewith. The flange 9 is integral with the shell and the flange 10 is separate therefrom and is bolted thereto so as to permit the assembling of the parts. The shell 55 is slotted endwise as is indicated in cross

section in Fig. 5, at 12 places. Through each of the slots so formed extend the piston blades 11. The shell is bored out to a cylindrical recess in line with each of these slots, as is shown at 11^a in Fig. 5. The piston 60 blades 11 extend through these slots and the segmental space left between the blades and the shell is filled in with segmental packing 11^b, which packing may be either of metal or fiber, as may be desired. The piston blade 11 makes a snug fit with the slots opening in the shell 8 with which it engages, so that its motion is always radial to said shell.

65 Each of the piston blades is provided with the arms 12 and 13 which extend outwardly from the inner end thereof, which arms are parallel to the piston blade. Sufficient space is provided between said arms and their piston blade to afford clearance for the casing and for the flanges of the piston shell. Inside of the piston shell is provided the governing shaft 14, which shaft is provided with a floating suspension which 70 will now be described.

75 Loosely mounted upon this shaft are the wheels 15 and 16. On each end of the shaft is provided a nut 17 and 18. Interposed between the wheels and the respective nuts are the compression springs 19 and 20. The ends of the arms 12 and 13 on the piston 80 blades are turned out at the top and are slightly hooked underneath. The centers of these out turned ends are in line with the outer edge of the piston blade. Interposed between these out turned ends of the arms 85 and the wheels 15 and 16 are the links 21, which links have a U-shaped recess 22 at the top for the purpose of engaging the out turned ends of the arms 12 and 13, and have the segmental recess 23 at the bottom for the purpose of loosely engaging with the wheels 15 and 16. The wheels 15 and 16 are grooved for the purpose of receiving the ends of the links 21 and holding them 90 loosely and firmly in place. The shaft 14 and wheels 15 and 16 are concentric with the cylinder 2. When assembled the shaft, the springs, the wheels, the links and the blades all coöperate with each other to hold 95 all of the parts in their respective positions within the piston shell.

100 The links 23 are provided with a liberal bearing or engagement with the wheel so as to firmly seat themselves thereon, and to provide for this the links at their inner ends 105 110

are made to overlap each other, as shown in Fig. 5. By tightening the nuts 17 and 18 the piston blades may be forced outward into contact with the cylinder with any desired pressure. This pressure is transmitted through the compression springs 19 and 20 the wheels 15 and 16 which can move along the shaft and the links 21 which links may be termed compression links. Rigidly connected to the piston shell on each side thereof are the spiders 24 and 25, each of which terminates in a hub or boss which is keyed to the shafts 26 and 27 which constitute the driving shaft for the engine.

In the operation of the engine or motor, when the steam is admitted as shown in Fig. 5, the steam will pass through the port 7 and engage with the blades 11, causing the piston shell to rotate in the direction indicated by the arrow. The piston shell with the spiders will rotate around the center of the power shafts 26 and 27 shown in Figs. 1 and 2 while the piston blades and the governing shaft 14 will rotate around the center of the governing shaft shown in Figs. 5 and 6, with which shaft the engine cylinder is concentric. The spiders are made sufficiently large to afford ample clearance between them and the links 21, wheels 15, shaft 14 and other parts of the governing mechanism. The links 21 are cut away at 28 as indicated in Fig. 1, for the purpose of affording additional clearance between themselves and the arms 29 of the spider, it being apparent that during the rotation of the piston the inner ends of the links 23 will shift backward and forward on the wheels 15 and 16. It will also be apparent that the outer ends of the piston blades will be closer together when on the left of the cylinder, as shown in Fig. 5, and will be farther apart when they are on the right of the cylinder, as shown in Fig. 5. This constant approaching and receding of the outer ends of the piston blades from each other will cause the links 21 to move at their outer ends, rocking with their inner ends loosely around the wheels on which they have their bearing. The engine cylinder has the flanges 51 and 52 on either side thereof. These flanges are each pierced with a circular opening through which the piston shell extends. On these flanges the shell is supported and has its bearing, and by them it is held in place. These circular openings are eccentric to the center of the engine cylinder. The piston shell has the flange 10 on one end that is detachable and which is clamped in place after the shell and engine cylinder have been assembled. The flanges 9 and 10 on the piston shell engage on the outside of the flanges 51 and 52 of the cylinder and by them the piston shell is held against endwise movement.

As shown in Figs. 1 and 2, the piston shell

is mounted to rotate with the shafts 26 and 27, which shafts may be mounted to rotate in the bearings 53 and 54. These bearings are integral with the engine casing. (See Fig. 2). The various parts are intended to hold the piston cylinder in contact with the engine cylinder at the division plate 40 that is between the intake and exhaust ports. If desired the bearings 53 and 54 may be omitted and the piston shell and its shafts may be supported entirely with the engagement that the shell makes with the engine cylinder. The piston blades 11 will be radial to the engine cylinder when they are in line with both the power and governing shafts, and will be eccentric to the engine cylinder in all intermediate positions.

In Figs. 1, 3, 4 and 5 I have shown a special form of reversing valve to be used in connection with my engine. This valve consists of a valve stem 30 mounted to rotate in the valve chamber or seat 3. This valve seat has the opening 31 on one side thereof and the ports 4 and 5 on the opposite side thereof, which can be used interchangeably as admission or exhaust ports. The valve stem is perforated with the three-way opening 32 through which the fluid pressure is conducted from the port 31 to either of the ports 4 or 5, as may be desired. It is also provided with the exhaust ports 33 and 34 which can alternately be placed into engagement with the ports 4 or 5 for the purpose of taking care of the exhaust therefrom. The exhaust port 34 is specially shaped, as shown, so that it can be placed in the position indicated in Fig. 4, which will permit the steam or other fluid to rotate or circulate idly with the piston without interfering therewith. With the exhaust valve 34 placed in the position shown in Fig. 4, the piston may be permitted to run idly, its operation then being properly termed as coasting.

It is obvious that the center of rotation of the piston shell is eccentric to the engine cylinder and will cause the piston shell to have a relative sliding movement upon the piston blades as they rotate, increasing or decreasing the steam space and providing for the working of the steam or gas expansively on the piston blades during the rotation.

Having thus described my invention, what I claim as new and patentable is as follows:

1. In a rotary engine, the combination of a cylinder, radial piston blades therein, each of said piston blades having arms extending outwardly and upwardly from the inner end thereof, said arms being cut turned at the top, links engaging with the cut turned ends of said arms and extending inwardly, grooved wheels with which said links engage, a shaft on which said wheels are mounted, the outer ends of said blades moving substantially concentric with said shaft.
2. In a rotary engine, the combination of

a cylinder, a cylindrical piston shell mounted to rotate eccentrically therein, said shell being of smaller diameter than the cylinder, piston blades extending radially through 5 said shell and making contact with the inner surface of said cylinder, flanges on the outer edges of said piston shell engaging with the outer surface of the cylinder, said flanges being concentric with the circular 10 opening eccentrically located in the sides of the cylinder.

3. In a rotary engine the combination of a cylindrical piston shell, piston blades extending therethrough, a shaft extending 15 centrally through said shell, connections between said piston blades and said shaft for supporting said shaft.

4. In a rotary engine, the combination of a cylindrical piston shell, piston blades extending therethrough, a shaft extending through said shell, wheels on said shaft, compression links yieldingly engaging between said piston blades and said wheels.

5. In a rotary engine, the combination of 25 a cylindrical piston shell, piston blades extending therethrough, a shaft extending through said shell, wheels on said shaft, compression links yieldingly engaging between said piston blades and said wheels, 30 said compression links being slightly dished toward a compression spring on said shaft for holding said wheel in place against the thrust of said links.

6. In a rotary engine, the combination of 35 a cylinder, piston blades mounted to rotate therein, said blades being arranged less than 90 degrees apart, a single means for yieldingly holding said piston blades in contact with the cylinder during the rotation of said 40 blades.

7. In a rotary engine, the combination of a cylinder, piston blades mounted to rotate therein, means for yieldingly holding said piston blades in contact with the cylinder 45 during the rotation of said blades, said means comprising a shaft common to all of said blades, links extending diagonally from said shaft to said blades, springs on said shaft, said springs tending to move the ends 50 of said links inwardly along the shaft and tending to spread the outer ends of said links.

8. In a rotary engine, the combination of a cylinder, a cylindrical piston shell eccentrically mounted therein, piston blades extending through said shell and making contact with said cylinder, said piston blades moving radial to said piston shell and being mounted to swing to and from radial position with said cylinder during the rotation 60 of said blades.

9. In a rotary engine, the combination of a cylinder, a cylindrical piston shell mounted eccentrically therein, said piston shell 65 making contact with said cylinder at one

point, piston blades mounted in said piston shell moving radially thereto, said blades being radial to the cylinder at two points and being eccentric to the cylinder at intermediate points.

10. In a rotary engine, the combination of a cylinder, a cylindrical piston shell mounted eccentrically therein, said piston shell making contact with said cylinder at one point, piston blades mounted in said piston 70 shell moving radially thereto, said blades being radial to the cylinder at two points and being eccentric to the cylinder at intermediate points, means for holding all of said piston blades yieldingly in contact with 75 the cylinder during the rotation of said piston blades.

11. In a rotary engine, the combination of a cylinder, a piston shell eccentrically mounted to rotate therein, spiders connected 80 to the opposite ends of said piston shell, shafts connected to the ends of said spiders, said shaft terminating in the hubs of the spiders.

12. In a rotary engine, the combination 85 of a cylinder, a piston shell mounted to rotate therein, spiders connected to the opposite ends of said piston shell, shafts connected to the ends of said spiders, said shaft being concentric with said piston shell and 90 eccentric with the cylinder.

13. In a rotary engine, the combination of a cylinder, a piston shell mounted to rotate therein eccentric to the cylinder, spiders connected to the opposite ends of said piston 100 shell, shafts connected to the ends of said spiders, piston blades extending through said shell, a shaft extending through said piston shell, links connecting between said shaft and said piston blades, by which said 105 shaft is suspended from said piston blades.

14. In a rotary engine, the combination of a cylinder, a piston shell mounted to rotate therein eccentric to the cylinder, spiders connected to the opposite ends of said piston shell, shafts connected to the ends of said spiders, piston blades extending through said shell, a shaft extending through said piston shell, links connecting between said shaft and said piston blades, by which 115 said shaft is suspended from said piston blades, the arms of said spiders passing between said links.

15. In a rotary engine, the combination of a cylinder, piston blades mounted to rotate 120 therein, said piston blades having arms extending outwardly from the inner end thereof and then upwardly parallel to said blade and outwardly at the outer ends of said arms, the center of said arms at the outer 125 ends thereof being in line with the outer edge of the piston blade.

16. In a rotary engine, the combination of a piston blade having an inner and an outer end, a support for said piston blade 130

extending outside of said blade, the center of said support being in line with the outer edge of said blade.

17. A rotary engine having a cylinder 5 with a flange on each end thereof, a circular opening in each flange eccentric to the cylinder and a cylindrical shell revolving inside of said cylinder, said shell having a concentric flange on each end thereof, the 10 flanges in the shell overlapping and making close contact with the flanges on the cylinder.

18. In a rotary engine the combination of a cylinder, a piston shell mounted to 15 rotate therein, piston blades having arms on each side thereof mounted to slide radially in said piston shell, a governing mechanism for said piston blades to keep them in contact with the inner surface of said cylinder, 20 said governing mechanism comprising an auxiliary shaft with wheels thereon, links for supporting said shaft, said links having a sliding engagement with said wheels on said shaft, means for keeping said links in place, a power shaft suitably mounted to 25 said piston shell.

19. In a rotary engine the combination of a cylinder, a piston shell mounted to rotate therein, piston blades having arms on 30 each side thereof mounted to slide radially in said piston shell, a governing mechanism for said piston blades to keep them in contact with the inner surface of said cylinder,

said governing mechanism comprising an auxiliary shaft, a grooved pulley loosely 35 mounted on each end of said shaft, links engaging with the groove in said pulleys with one end thereof and the arms of said piston blades with the other end thereof, a compression spring mounted on said shaft 40 to hold said links in engagement with said grooved pulleys and the arms of said piston blades.

20. In a rotary engine the combination of a cylinder, a piston shell mounted to 45 rotate therein, piston blades having arms on each side thereof mounted to slide radially in said piston shell, a governing mechanism for said piston blades to keep them in contact with the inner surface of said 50 cylinder, said governing mechanism comprising an auxiliary shaft freely suspended by links having an engagement with said arms on said shaft, means for keeping said links in place, a power shaft suitably mounted 55 to said piston shell, a rotary valve connected to said cylinder having two separate exhaust ports, an inlet port diverging into two branches which may be brought alternately in line with the main inlet port. 60

In testimony whereof I affix my signature in presence of two witnesses.

ANTON METZLER.
